Primary Examiner — Susan Moon Lee(74) *Attorney, Agent, or Firm* — Lewis Roca Rothgerber LLP; Samantha A. Updegraff(57) **CLAIM**

I claim the ornamental design for a suet feeder, as shown and described.

DESCRIPTION

FIG. 1 is a perspective view of a suet feeder showing my new design;

FIG. 2 is a front view of a suet feeder;

FIG. 3 is a back view of a suet feeder;

FIG. 4 is a right side view of a suet feeder;

FIG. 5 is a left side view of a suet feeder;

FIG. 6 is a top view of a suet feeder; and,

FIG. 7 is a bottom view of a suet feeder.

Broken lines and unshaded portions contained within broken lines are not claimed.

1 Claim, 7 Drawing Sheets(56)
